UNITED STATES PATENT OFFICE.

WILLARD C. CHAPIN AND JAMES H. PETTEE, OF ROCKLAND, MAINE.

RADIATOR FOR INTERNAL-COMBUSTION ENGINES.

Application filed August 12, 1922. Serial No. 581,501.

To all whom it may concern:

Be it known that we, WILLARD COLLINS CHAPIN and JAMES HERBERT PETTEE, citizens of the United States, and residents 5 of Rockland, in the county of Knox and State of Maine, have invented certain new and useful Improvements in Radiators for Internal-Combustion Engines, of which the following is a specification.

10 This invention relates to improvements in radiators for internal combustion engines.

The present invention particularly relates to structural features in radiators and has for its purpose or object to provide a radiator employing tubular members for radiating heat which may be easily replaced by a new tube without dismantling the radiator to any great extent.

It is also an object of the invention that 20 the radiator be adapted to be mounted upon a motor vehicle and be neat in appearance.

It is also within the scope of the objects of the invention that the radiator be inexpensive to manufacture and durable.

25 Other objects relating to details of construction will hereinafter appear.

The invention is illustrated by way of example in the accompanying drawings, in which,

30 Figure 1 is a view in front elevation of a radiator embodying the present invention when applied to a motor vehicle and showing the same partly in section to more clearly illustrate the invention.

35 Figure 2 is a vertical transverse sectional view of the same.

Figure 3 is a perspective view of the radiator tubes and connected tank sections.

40 Figure 4 is a group perspective illustrating the manner in which the sections of radiator casing are connected to each other, and

Figure 5 is a similar view showing a radiator tube and nuts therefor.

45 Referring to the drawings more particularly, T indicates generally the upper tank of the radiator, T' the lower tank, and R the radiator tubes. Each of the tanks T and T' comprise an upper section 10 and a lower section 10'. Each bottom section 10' of the tanks is pin-shaped and provided with a bolting flange 11. The top section 10 of the tank T is rectangular in cross section with sloping end walls and about its edge is provided with a bolting flange 12. The sections 10 and 10' of the tank T are secured together

by bolts 13 which are provided with wing nuts 14. The top section is also provided with a neck 15 having a removable cap 16. From the inner side wall of the top section of tank 60 T there extends a nipple 17 with which the induction pipe or hose 18 may be connected. Also the wall may be provided with a flange 19 upon which the forward end of the associated hood 20 may rest. 65

The tubes R extend through the top section 10 of tank T and the bottom section 10' of the tank T thereby establishing communication between these tanks. Each tube carries a nut 21 threaded upon each of its ends and a washer may be interposed between each nut and associated tank section whereby to insure a tight closure. A plurality of rods R' are employed for holding the tanks T and T' in spaced relation, each rod having a nut 22 at each end as shown. To further support the rods there is provided a bridge plate 23 through which said rods and tubes pass. Each of the rods R' carries a pair of nuts 24 by which they may be 80 locked with relation to the plate 23. The ends of the plate 23 are supported by the frame members 25 of the vehicle upon which the radiator is mounted. 75

A plate 27 is disposed beneath the bottom section of tank T' and riveted thereto as at 28. Each end of the plate 27 terminates in an upwardly extending flange 30 which terminates in an L-shaped section 31, the horizontal and end portion of which 90 is bolted to the associated vehicle frame member 25 as at 32. 85

The top section 10 of the tank T is formed at each end with a rib 33 which terminates along its edge in a downwardly curved lip 95 34. The forward side of the same section is formed with a similar rib and lip as at 35 and 36, respectively (Figure 2). A flap or wing 37 is positioned upon the forward side of the tank T, said flap or wing being substantially arcuate in cross section and its upper end terminating in a curved lip 38 which is adapted to be hooked to the curved lip 36 occurring upon the front side of the tank T for supporting the wing 37. The 100 wing 37 merely adds to the appearance of the radiator when mounted upon a motor vehicle. To further enclose the radiator there is provided two side sections 39, each section having its lower end formed with a 105 flange 40 adapted to be positioned upon the associated vehicle frame member 25 and 110

having its upper end formed with a lip 41 adapted to engage with the associated lip 34 of the tank T.

For the lower and forward end of the 5 radiator there is provided a cover or casing section generally indicated by the reference numeral 44 which consists in sheet metal as shown in Figure 1 and having upwardly extending end portions 45 formed therewith 10 which may be secured to the side frame members 25 of the associated motor vehicle. The lower edge of the member 44 is provided with an inwardly extending flange 46. The bridge plate 23 is formed with a 15 downwardly extending angular flange 47 which terminates in an inwardly extending portion 48 and between the lower end of the flange 47 and the similar edge of the plate 44 there is supported a plate 49, said 20 plate being secured by the means of bolts 50 thus enclosing the lower end of the radiator. The bolts 51 may be employed for securing the side members 39, the plate 44 and the plate 23 to the side frame members 25 of the vehicle upon which the radiator 25 may be mounted.

Between the sections of each tank T and T' there may be interposed a rubber gasket as at 53 and the lower tank may have its 30 lower section 10' provided with a nipple 54 to which an outlet housing or pipe 55 may be connected.

The radiator may also be provided with 35 radiating fins 56 which may extend transversely of the radiator and be superposed as shown. The fins 56 may consist in sheets of brass and the tube R and rods R' may extend through these sheets. The sheets may be secured to the rods R' for holding the 40 same in position and at the same time permitting the tubes R to be easily removed.

In the use of the present device the same 45 is mounted upon the chassis frame of a motor vehicle and properly connected. The different members forming an enclosure for the casing are of course properly positioned and as a whole the radiator presents a neat appearance. The water entering the tank

T may pass through the tubes R and into the lower tank and from thence through the 50 outlet nipple 54. Radiation of heat is principally effected through the tubes R and also aided by the fins 56.

It is important here to note that should either of the tubes R become punctured the 55 same can be easily replaced. In fact any unskilled mechanic may withdraw one of the tubes R and substitute a new tube therefor. A supply of tubes R may be carried in the tool box of the motor vehicle and 60 thus at all times providing means for repairing the radiator.

It is believed apparent from the description heretofore given of the invention that the particular manner in which the structural elements are disclosed cooperate for producing a durable and efficient radiator 65 may be understood without further description.

What we claim is:

1. A radiator comprising a pair of tanks communicating with each other through a plurality of tubes and each tube having nuts threaded thereon for removably holding the same positioned, a plurality or rods extending between the tanks for supporting the same in spaced relation, a bridge plate through which said rods may pass and also the tubes, and means whereby said rods may be locked against movement with relation 75 to said bridge plate.

2. A radiator comprising a pair of tanks communicating with each other through a plurality of tubes and each tube having nuts threaded thereon removably for holding the same in position, a plurality of rods extending between the tanks for supporting the same in spaced relation, a bridge plate through which said rods may pass and also the tubes, means whereby said rods may be locked against movement with relation to 80 said bridge plate, and means whereby the ends of the bridge plate may be supported.

W. C. CHAPIN.
J. H. PETTEE.
